UNITED STATES PATENT OFFICE.

WILLIAM C. JOHNSON, OF MINNEAPOLIS, MINNESOTA.

AIR-PREHEATING ATTACHMENT FOR INTERNAL-COMBUSTION ENGINES.

Application filed November 9, 1918. Serial No. 261,840.

To all whom it may concern:

Be it known that I, WILLIAM C. JOHNSON, a citizen of the United States, residing at Minneapolis, in the county of Hennepin and State of Minnesota, have invented certain new and useful Improvements in Air-Preheating Attachments for Internal-Combustion Engines; and I do hereby declare the following to be a full, clear, and exact description of the invention, such as will enable others skilled in the art to which it appertains to make and use the same.

My invention has for its object to provide an extremely simple and highly efficient air preheating attachment for internal combustion engines; and to such ends, generally stated, the invention consists of the novel devices and combinations of devices herein-after described and defined in the claims.

Particularly, this improved preheater is adapted for application to the exhaust manifold of the engines of Ford automobiles, but is, nevertheless, capable of application to various other types of engines.

The invention is illustrated in the accompanying drawings wherein like characters indicate like parts throughout the several views. Referring to the drawings,

Fig. 1 is a view in side elevation showing, in diagram, portions of the engine and associated devices of an automobile, such as a Ford, and illustrating my improved air preheating device applied thereto.

Fig. 2 is a side elevation of the air preheater and the exhaust manifold, both being removable from the engine, some parts being broken away and some parts being in section;

Fig. 3 is a left end elevation of the parts shown in Fig. 2; and

Fig. 4 is an enlarged section on the line 4-4 of Fig. 1.

Of the ordinary parts of the automobile illustrated in the drawings, the numeral 5 indicates the cylinder casting, the numeral 6 the intake manifold, the numeral 7 the carbureter, the numeral 8 the exhaust manifold, the numeral 9 the radiator and the numeral 10 a fan.

The improved air preheater is preferably made from sheet metal and the body 11 thereof is bent upon itself to form a housing comprising an outer side clamping plate 12 and an inner side trough-like structure 13. The trough structure 13 has a transverse

end flange 14, and beyond this flange 14 the interior of the body, formed as above stated, leads to the upper portion of a depending air tube 15. The said body is open at its front end for the admission of air and when it is clamped onto the exhaust manifold 8, as best shown in Figs. 2 and 4, it will be firmly held in position and there will be an air space or channel 16 over the entire top and portion of the sides of such manifold. This channel 16 directs the air which is drawn in from the front over the hot exhaust manifold and into the upper end of the depending tube 15. There will be sufficient spring in the body of the preheater to securely hold the same on the manifold and the air drawn through the channel 16 will be heated to quite high temperature before it passes into the tube 15. From the tube 15, the hot or warm air is directed to the air intake of the carbureter 7, preferably through an adjustable elbow 17 that is telescoped into the said air intake port and into the lower end of the tube 15.

It is a well known fact that moistened air increases the efficiency of an internal combustion engine. To provide for moistening of the air, I run a flexible tube 18 into the receiving end of the trough 13 and air channel 16 and connect the front end of said tube 18 to the top of the radiator, that is either directly to the top of the upper water pan thereof, as shown in Fig. 1, or, if desired, indirectly to the said upper pan through the customary overflow tube not shown. With this arrangement, the moist vapor is drawn from the radiator to moisten the warm air delivered to the carbureter through the preheating device.

The above described attachment or preheating device may be made at very small cost and, in practice, has been found highly efficient for the purposes had in view. Preferably, the interior of the air channel 16 is lined with asbestos paper or similar heat insulating material.

The housing made up of a body of air preheater is preferably constructed of sheet metal and when thus constructed, its sides are capable of springing so that they will adapt themselves to the manifold and frictionally clamp the housing in working position on the manifold. In case water should be condensed in the vapor tube 18, or water should be drawn from the radiator

through said tube, it will run into the trough 13, but the end flange 14 will prevent the same from running into the air tube 15. Water will thus be prevented 5 from getting to the carbureter, and as the bottom of the trough 13 is forwardly inclined, such water will run downward and forward and out of the front end of said trough.

10 It is evident that with the air preheater applied as described, the air, partly by the action of the fan and partly by the movement of the external air under forward movement of the automobile will be forced 15 through the air channel of the preheater, thereby greatly assisting the suction produced in the carbureter in drawing the pre-heated air to the carbureter.

What I claim is:

20 1. An air preheating device adapted to be applied to the exhaust manifold of internal combustion engines having in combination, a sheet metal housing bent to form a narrow heating chamber directly over said 25 manifold and a vaporizing trough at the side of said manifold adapted to carry off the condensed moisture, a vapor tube connected from the top of the radiator into the said trough, said housing having an open 30 end and an air tube an opening into said trough at one end and adapted to be connected to the carburetor at its other end.

2. An air preheating device adapted to be applied to the exhaust manifold of internal 35 combustion engines having in combination a housing bent to form a narrow heating chamber over said manifold and a connecting vaporizing trough at the side of the said manifold, said housing having 40 an open end, an air tube opening into said trough and adapted to be connected with the carburetor at its other end and a transverse upright flange at the bottom of the

said trough operative to prevent condensed water from running into the said air tube. 45

3. An air preheating device for internal combustion engines in the form of a channel-shaped housing adapted to be clamped onto opposite sides of the exhaust manifold of the engine, said housing, at one side, being in the form of a trough that terminates short of the rear end of said housing, said housing, at its rear end, beyond said trough, having a depending air tube adapted for connection to the carbureter of the engine, 50 the said housing being of sheet metal and the sides thereof having a spring yielding action adapting said housing to adjust itself to the exhaust manifold and to frictionally clamp itself in position thereon. 55

4. An air preheating device adapted to be applied to the exhaust manifold of an automobile engine comprising a sheet metal housing extending longitudinally over said manifold having a vertical side contacting one side of said manifold, an upwardly converging top portion, and a rectangular trough formed at its other side, the inner side of which trough contacts the other side of said manifold, said housing and trough having an open front end, a conduit entering the front end of the trough and being adapted to be connected to the radiator of the engine, a downwardly extending conduit communicating with the rear end of 75 said housing, said trough having a vertically extending end portion adjacent said latter conduit adapted to prevent moisture being drawn into said conduit. 70

In testimony whereof I affix my signature 80 in presence of two witnesses.

WILLIAM C. JOHNSON.
